(57) **CLAIM**

The ornamental design for an edible stick, as shown and described.

DESCRIPTION

FIG. 1 is top perspective view of an edible stick; FIG. 2 is a bottom perspective view of the edible stick of FIG. 1;

FIG. 3 is a front elevational view thereof;

FIG. 4 is a top plan view thereof;

FIG. 5 is a bottom plan view thereof; and,

FIG. 6 is a left side elevational view thereof.

A rear elevational view is not shown because it is a mirror image of the front elevational view shown in FIG. 3. A right side elevational view is not shown because it is a mirror image of the left side elevational view shown in FIG. 6. The stipple shading in the drawings indicates that the surfaces have a light texture.
